(57) **CLAIM**

The ornamental design for a painting toolbox, as shown and described.

DESCRIPTION

FIG. 1 is a front, right and top perspective view of a painting toolbox, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a cross-sectional view of the painting toolbox of FIG. 1, taken along section line 9-9 as depicted in FIG. 3; and,

FIG. 10 is another front, right and top perspective view of the painting toolbox in an alternate configuration.

The broken lines depict portions of the painting toolbox that form no part of the claimed design.

1 Claim, 10 Drawing Sheets
